UNITED STATES PATENT OFFICE.

CHARLES A. HOMAN, OF ST. LOUIS, MISSOURI.

DESIGN FOR AN EASTERN-STAR SIGNET.

56,875.

Specification for Design.

Patented Jan. 4, 1921.

Application filed June 3, 1920. Serial No. 386,366. Term of patent 14 years.

To all whom it may concern:

Be it known that I, CHAS A. HOMAN, a citizen of the United States, residing at St. Louis, Missouri, have invented a new, original, and ornamental Design for an Eastern- Star Signet, of which the following is a specification, reference being had to the accompanying drawing, forming part thereof.

The figure is a plan front view of an Eastern Star signet showing my new design.

I claim:

The ornamental design for an Eastern Star signet, as shown.

CHAS. A. HOMAN.
